[57] CLAIM

The ornamental design for a plate for computer printer, as shown and described.

DESCRIPTION

FIG. 1 is a front view of a plate for computer printer showing our new design;

FIG. 2 is a top plan view thereof; and,

FIG. 3 is an enlarged partial view thereof.

The broken lines are for purposes of illustration only and form no part of the claimed design.

1 Claim, 3 Drawing Sheets

FIG. 1

FIG. 2*FIG. 3*
